His Atty.

UNITED STATES PATENT OFFICE

ROLAND J. OLANDER, OF CHICAGO, ILLINOIS, ASSIGNOR TO W. H. MINER, INC., OF CHICAGO, ILLINOIS, A CORPORATION OF DELAWARE

CAR CONSTRUCTION

Application filed January 30, 1930. Serial No. 424,499.

This invention relates to improvements in car construction, and especially the center pin arrangement thereof for connecting the body and truck bolsters.

5 One object of the invention is to provide a simple and efficient center pin construction for connecting the body and truck bolsters of railway cars having shouldered engagement with the bolsters and which is readily attachable and removable, the pin being made of a plurality of parts so designed that maximum shouldered engagement with the bolsters is obtained by providing head portions at opposite ends of each section and also on the filler 10 member, which cooperate with shoulders on both bolsters.

A further object of the invention is to provide a center pin construction of the character indicated in the preceding paragraph, 20 composed of a minimum number of parts, while at the same time providing ample shouldered engagement with the bolsters, the pin being preferably composed of a pair of outer sections, each having shouldered engagement 25 with both bolsters, and spreading or filler means between said sections, comprising a sectional spreading member including two main sections and a wedge plate interposed therebetween, both main sections having shouldered engagement with both bolsters and said wedge plate being held in wedging 30 engagement through the weight thereof.

Other objects of the invention will more clearly appear from the description and 35 claims hereinafter following.

In the drawing, forming a part of this specification, Figure 1 is a top plan view of a portion of a body bolster of a railway car illustrating my improvements in connection 40 therewith. Figure 2 is a vertical, sectional view, corresponding substantially to the line 2-2 of Figure 1. Figure 3 is a bottom plan view of the construction illustrated in Figure 2. And Figure 4 is a detailed perspective view of one of the members forming the filler means of my improved center pin construction.

In said drawings, 10 designates the body bolster and 11 the truck bolster of a railway 45 car. The body bolster is provided with the

usual depending bearing portion 12, which is seated in a bearing pocket 13 of a bearing block 14 mounted on top of the truck bolster 11. As clearly shown in Figure 2, the bearing block 14 is seated in a pocket 15 provided at the top of the truck bolster and is held against movement with respect to said bolster. The body and truck bolsters and the bearing block 14 are provided with aligned center pin receiving openings 16, 17 and 18 respectively, which are preferably all of the same size in cross section. The bearing block 14 is provided with an upstanding flange 19 surrounding the pin receiving opening thereof, the flange engaging within a bearing 65 opening 20 provided in the bottom face of the bearing projection of the body bolster. At the upper portion thereof, the body bolster has a head receiving pocket or opening 21, which is in alignment with the center pin receiving opening 16 of said bolster, but of larger diameter, thereby providing an annular retaining shoulder 22 at the bottom of said pocket and surrounding the outer end of the pin receiving opening. The truck bolster is 75 provided with a similar pocket 23, which is in alignment with the opening 17 thereof, but is of greater width so as to provide a retaining shoulder 24 at the inner end of the pocket and surrounding the outer end of the pin receiving opening 17. 80

My improved center pin construction comprises broadly a pair of outer sections A—A and a spreading means comprising a pair of outer members B—B and a wedge plate member C.

The outer sections A—A of the pin are of similar design, each having a shank portion 25 disposed within the center pin openings of the bolsters and enlargements 26 and 27 at the top and bottom ends thereof respectively. The enlargement 26 at the upper end of each section A is adapted to overhang the shoulder of the body bolster and the enlargement 27 at the lower end of said section 90 overhangs the shoulder 24 of the truck bolster. The two sections A—A are held apart by the spreading means comprising the members B—B and the wedge plate C. Each of the members B comprises a shank portion 95

28 and enlargements 29 and 30 at the top and bottom ends of said shank portion. The enlargements 29 and 30 are adapted to overhang the shoulders of the body and truck bolsters respectively, as clearly shown in Figure 2. The enlargements 29 at the upper ends of the sections B are in horizontal alinement with the head members 26—26 of the sections A and form continuous flange members in connection therewith. As most clearly shown in Figure 3, the enlargements 27—27 at the bottom ends of the sections A—A are of smaller size than the enlargements 26—26 at the upper ends thereof, the former being 15 so designed that the same will pass through the center pin receiving openings of the bolsters when the filler member is omitted, to facilitate assembling of the pin with the body and truck bolsters. The outer members 20 B—B of the filling means are held apart and in shouldered engagement with the bolsters by the wedge plate C, the latter engaging between the inner vertical edge portions of the two members B, as clearly shown in Figure 25 2. The assembled pin completely fills the center pin receiving openings 16 and 17 of the bolsters and the head member formed by the head sections at the upper end of the pin substantially fits the head receiving pocket 21.

30 In order to space the head members at the bottom end of the pin, the proper distance from the shoulder 24 of the truck bolster, a plurality of shims 31—31 are interposed between the shoulder 22 of the body bolster and the head members at that end of the pin. As shown in Figure 2, three such shims are employed, it being understood that the number may be varied as desired so as to obtain the proper spacing between the head members 35 at the bottom end of the pin and the shoulder 24 of the truck bolster.

40

In applying my improved center pin to the bolsters of a railway car, the sections A—A are applied by inserting the same downwardly 45 through the pocket 21 of the body bolster, the two sections A being preferably inserted successively. The enlargement 27 at the bottom end of each section A is of such a size that it will pass freely through the pin receiving 50 openings of the bolsters while the section is being applied by inserting the same through the pocket 21 of the body bolster. When one of the sections A has been fully inserted, the same is displaced laterally so that the enlargements thereof overhang the shoulders of the bolsters. Then the other section A is applied in a similar manner by inserting the same through the top of the body bolster and is displaced laterally when fully inserted to 55 engage the enlargements thereof over the shoulders of the bolsters. The filler means is then applied by successively inserting the members B—B upwardly through the pocket 23 of the truck bolster. After the two sections B have been applied, the wedge plate

C is inserted therebetween by applying the same through the pocket 21 of the body bolster. Through the wedge spreading action of the member C, the upper ends of the members B—B are spread apart, thereby bringing the same in overlapping relation with the shoulder of the body bolster. As will be understood, the proper number of shims are placed upon the shoulder 22 of the body bolster before the pin is applied. In order to facilitate withdrawal of the wedge plate C, the same is provided with a tool receiving opening 32 at the upper end thereof. Each of the sections A of the pin is also provided with an upstanding eye member 33 at the upper end thereof with which a tool may be engaged for lifting the same out of the openings of the bolsters.

When it is desired to separate the bolsters, the wedge plate C is first removed by lifting the same upwardly through the pocket of the body bolster. The upper end portions of the two sections B—B of the filler member are then swung inwardly so as to contract the same, whereby the enlarged portions 29—29 at the upper ends thereof will pass through the pin receiving openings of the bolsters. These two members are then dropped through the truck bolster. After removal of the filler members B—B, each section A may be displaced laterally so as to aline the enlargements 27—27 at the bottom end thereof with the openings of the bolsters and permit lifting of the sections of the pin out of said openings.

I have herein shown and described what I now consider the preferred manner of carrying out my invention, but the same is merely illustrative and I contemplate all changes and modifications that come within the scope of the claims appended hereto.

I claim:

1. In car construction, the combination with body and truck bolsters having alined center pin receiving openings and each bolster having a retaining shoulder adjacent the outer end of its opening; of a sectional center pin connecting said bolsters, said pin including a plurality of outer sections, each having enlargements at opposite ends thereof having shouldered engagement with said shoulders of the bolsters respectively; and filler means for holding said sections separated and in shouldered engagement with the bolsters, said filler means including a plurality of separable members each having enlargements at opposite ends having shouldered engagement with said retaining shoulders of the bolsters; and wedge means between said members for holding the same separated and in shouldered engagement with the bolster shoulders.

2. In car construction, the combination with body and truck bolsters having alined center pin receiving openings, each bolster

having a shoulder adjacent the outer end of its opening; of a center pin connecting said bolsters, said pin including a pair of outer sections and a sectional filler means between said outer sections, said filler means including a pair of outer members and a wedge member between said outer members for holding the same separated, each of said outer sections of each of said outer members having heads at opposite ends thereof having shouldered engagement with the shoulders of the body and truck bolsters respectively.

3. In car construction, the combination with body and truck bolsters having aligned center pin receiving openings, each bolster having a shoulder adjacent the outer end of its opening; of a sectional center pin connecting said bolsters, said pin including a pair of outer sections and a sectional filler plate member between said outer section, said filler plate member including outer sections, said outer sections of the filler plate member and said outer sections of the pin each having head members at opposite ends thereof having shouldered engagement with the shoulders of the body and truck bolsters respectively.

In witness that I claim the foregoing I have hereunto subscribed my name this 28th day of January, 1930.

30 ROLAND J. OLANDER.
